UNITED STATES PATENT OFFICE.

FREDERICK L. MCGAHAN, OF LOS ANGELES, CALIFORNIA.

CONDENSING AND VACUUM DRAFT MECHANISM FOR FURNACES.

1,217,100.

Specification of Letters Patent. Patented Feb. 20, 1917.

Application filed April 9, 1914. Serial No. 830,617.

To all whom it may concern:

Be it known that I, FREDERICK L. MCGAHAN, a citizen of the United States, residing at Los Angeles, in the county of Los Angeles and State of California, have invented a new and useful Condensing and Vacuum Draft Mechanism for Furnaces, of which the following is a specification.

In the treatment of ores and the reduction from the raw state of metal and other substances, a great loss of valuable matter has hitherto been the result of smelting operations with the use of the prevailing types of smelting and reduction apparatus, inasmuch as no practical method of treating and preserving the unconsumed gases from the furnace has been devised or used in connection with the apparatus, and as a result, the finer particles of matter which form a part of and are carried off with the gases from the furnace, and which comprise frequently in no small quantity, some of the valuable metals, are vented through the stack and distributed broadcast over the ground in the vicinity of the plant.

It is, therefore, an object of my invention to provide a means of treating the unconsumed gases from the furnace so that the fine particles may be preserved, and whereby all of the valuable matter in these gases may be separated therefrom, and the gases after the separation further utilized in the operation of the plant.

A further object is to provide a means which may be used in connection with any fuel burning plant for the production of power, light or heat, whereby all of the heat units in the combustible matter may be used and none of the valuable units or elements allowed to escape.

Other objects may appear in the subjoined detail description of my apparatus, as illustrated in the accompanying drawings forming a part of this application, and in which:

Figure 1 is a plan of my apparatus with parts of the structure broken away;

Fig. 2 is a side elevation, partly in section;

Fig. 3 is a sectional elevation of the condenser on the line x^3-x^3 , Fig. 1;

Fig. 4 is a sectional plan of the same on the line x^4-x^4 , Fig. 3.

Fig. 5 is a sectional plan of the same on the line x^5-x^5 , Fig. 3.

Fig. 6 is a sectional plan of the same on the line x^6-x^6 , Fig. 3. 55

Fig. 7 is a fragmentary plan of the roller bearings;

Fig. 8 is a partial enlarged elevation of the condenser and governor connections;

Fig. 9 is an end elevation of the apparatus;

Fig. 10 is a sectional plan of the governor yoke and sleeve on the line $x^{10}-x^{10}$, Fig. 8.

Similar characters of reference indicate the same parts throughout the specifications 65 and the several views of the drawings.

Reference is had to a previous application filed by me in the United States Patent Office on the 26th day of February, 1914, Serial No. 822,234, for a process for the treatment of ores and substances, in which is shown certain other elements adapted to coöperate with this invention in the treatment of ores and substances of various character, and in which a more elaborate and detailed description of the entire plant and the functions thereof, is given. 70 75

It is intended to include in this application, only the condenser and its co-acting elements, but it is thought necessary to describe in a limited way and to partially illustrate, several other of the elements of the plant, in order that a clear idea of the operation and functions of my invention may be had, and its relation to the other elements 80 85 of the plant, not shown, established.

My condenser comprises the base 1, which is adapted to be mounted on a suitable structure, not shown; the condenser shell 2 which is cylindrical in form; and the head 3; the shell 2 being suitably secured to the base 1 by the cap screws 4, and the head 3 being secured to the top of the shell 2 by the bolts 5. The shell 2 has the gas chamber 6 at the top, which is provided with the inlet 7 secured to the shell by the cap screws 8 and to the main stack 9 by the bolts 10, and at right angles to the inlet 7 this chamber is also provided with the gas outlet 11, which is similarly secured to the shell 2 and is connected with a pipe 12 leading to a suitable induction fan, not shown, in order that certain of the gases, as hereinafter described, may be drawn from the condenser for use in the operation of the plant. The central, 90 95 100 105 or condensing portion of the shell 2, 13, is

conical in form and near its top is provided with the water inlet 15 which may be placed at any convenient angle and is adapted to be connected with a source of water supply, 5 and the lower end of the chamber 13 has an annular shoulder 16 and a funnel shaped opening 17 for discharging the water therefrom.

The lower chamber 14 of the shell 2 has a 10 funnel 27 which is secured to the wall of the chamber by means of the bolts 38 through the flange 39, and this funnel serves to divide the chamber 14 into the two chambers 35 and 36, the upper of which serves as 15 a vacuum chamber and the lower as a water chamber.

At the junction of the chambers 6 and 13, I provide the internal annular flange 18 on the shell 2 which is tapered slightly toward 20 the wall of the shell and adapted to receive a plurality of rollers 19, as shown in Fig. 7 and at the junction of the chambers 13 and 14 I provide the annular flange 16 having a ball race 20 on its upper side adapted to 25 receive the ball bearings 21. The vertical shaft 22 is journaled in the bearings 23 on the base 1 and 24 on the head 3, and is provided with the fan 25 adapted to revolve in the lower portion of the chamber 6, and the 30 centrifugal water spreader 26 adapted to revolve in the chamber 13, the water spreader 26 being conical in form and having the hubs 27 and 28 at the top and bottom, respectively, by means of which it may 35 be fixed on the shaft 22. The periphery of the water spreader 26 has the helical vanes 29 adapted to fit snugly into the chamber, the lower end has the internal flange 30 with a ball race 31 which is adapted to register 40 with the race 20 on the flange 16 and adapted to engage the upper portion of the balls 21, the upper end has the external flange 32 tapered on the lower side to conform to and adapted to rest upon the rollers 19, and the 45 flanges 30 and 32 are connected with the hubs 27 and 28, respectively, by the radial arms 33 and 34.

The vertical shaft 22 extends upwardly through and above the head 3 for a suitable 50 distance, is provided with the bevel gear 40 adjacent to the head 3, and with the vertically slideable sleeve 41 which has an annular groove 42 adapted to be engaged by the rollers 43 which are revolvably mounted on 55 the ends 44 of the yoke 45. The upper end 46 of the shaft 22 is reduced and has the sleeve 47 revolvably thereon and adapted to be held by the nut 48. The governor rods 50 are pivoted at their upper ends to suitable ears 49 on the sleeve 47, and at their lower ends are provided with the ordinary 60 governor balls 51, the rods 50 and the balls 51 being held at an angle to the shaft 22 by means of the rods 52 which are pivoted at

their lower ends to suitable ears 53 on the 65 sliding sleeve 41, and at their upper ends 54, are slideable on the rods 50. The shaft 22 is provided with the spring 55 which is interposed and compressed between the sleeve 41 and the bevel gear 40, and the upward 70 movement of the sleeve 41 is limited by means of the set collar 56 held tight on the shaft 22 by the set screw 57.

The governor yoke 45 is pivoted near its outer end in the bracket 58 which is secured to the head 3 by the bolts 59, and the outer end of the yoke is connected with the quick opening valve 60 in the water inlet pipe 15, by means of the vertical link 61 pivoted at its upper end to the yoke 45 and 75 at its lower end to the outer end of the valve lever 62. A pipe 63, as shown in Fig. 8, is provided, which parallels the pipe 15 to a suitable water storage tank, not shown, and to which both of said pipes are connected, 80 the pipe 63 being also connected with a suitable pump, (not shown) and provided with a suitable valve 67, and the two pipes are cross connected by means of the T's 64 and 65 and the valve 66. The arrangement 85 shown, serving to provide a means for filling the storage tanks, and as a means of supplying water to the water spreader direct from a pump in the event that the water in the tanks should become exhausted. 90

The water from the pipe 15 is directed against the vanes on the water spreader 26, which because of its frictionless bearings, will be caused to revolve at a high speed, and in the event that the speed of the 100 spreader should become excessive, the centrifugal force will cause the balls 51 to swing outwardly, the sleeve 41 will be caused to rise on the shaft 22, the outer end of the yoke 45 will swing downwardly 105 on its pivot, and the valve lever 62 will wholly or partially close the valve 60, thus accommodating the speed of the water spreader to the quantity of water delivered through the valve 60, and preventing an excessive speed of the former. The operation of the valve 60 may be regulated by changing the position of the set collar 56 on the upper end of the shaft 22, and a resiliency is afforded in the vertical movement 110 of the sleeve 41 by means of the spring 55.

In the operation of the spreader, the water from its periphery will be discharged at the bottom through the funnel shaped opening 17, and in its discharge from the spreader 120 will be formed into a sheet, from whence it will be directed through the funnel 27 into the lower chamber 36, the funnel 27 serving to prevent the accumulation of the water in the vacuum chamber 35. The base 1 forming the bottom of the water chamber 36, is provided with a plurality of discharge openings 68 connected with the discharge pipes 125

69 leading to the separator tanks 77, and these openings 68 are arranged, preferably at equal distances apart, and concentrically with regard to the base 1.

5 The fan 25, which may be of any suitable type, is of the induction type and serves to draw the heavier gases and substances from the stack 9 and the chamber 6 into the condensing portion of the water spreader 26, the 10 temperature of the latter being cooler than that of the stack 9 at which point a partial condensation of the fumes will be effected and the condensed solid matter will fall into the lower portion of the condenser, while the 15 more volatile substances will be carried off through the outlet 11.

At one side of the condenser, I provide a suitable structure 70 comprising the vertical columns 71, the longitudinal members 72, the 20 lateral members 73, and the platform 74; the entire structure being suitably braced and connected with the condenser by the angle brackets 75. In the center of the structure 70 and on a line with the center of the shaft 25 22 of the condenser, I arrange a plurality of vertically disposed vacuum tubes 76, the lower ends of which extend down into and near the bottom of the separator tanks 77, the upper ends extending above the platform 30 74 and being provided with the heads 78, and the lower ends being secured to the top of the separator tanks 77 by the flanges 79. These vacuum tubes have an upper chamber 84 and a lower chamber 82, separated by the 35 partition 80 which is provided with the port 81 for affording communication between the two chambers, the chamber 82 is connected with the vacuum chamber 35 of the condenser, by means of the pipes 83 arranged at 40 equal distances apart on the condenser and the upper chambers 84 are connected with the stack 9 by the pipes 85, the connection of the pipes 85 with the stack 9, being arranged at suitable intervals, as may be found convenient.

The crank shaft 86 is revolvably mounted in the bearings 87 and 88 secured to the head 3 of the condenser and in the bearings 88 secured to the standards 89 which are mounted upon the structure 70. The crank shaft is provided with a plurality of cranks 90, one for each of the tubes 76 and each of the cranks being centrally positioned above its respective tube. The piston rods 91 are 55 pivoted to the connecting rods 92 at their upper ends and secured to the pistons 93 at their lower ends; the connecting rods 92 are pivoted at their upper ends to the cranks 90, and the pistons 93 are adapted to slide vertically in the upper chambers 84 of the 60 vacuum tubes 76 and to simultaneously open and close the ports 81 and 96. The piston rods 91 are provided with the compression springs 94 adapted to compress between the

pistons 93 and the hubs 95 on the heads 78 65 and thus provide a resiliency in the operation of the pistons.

The crank shaft 86 has a bevel gear 97 on its inner end adapted to mesh with and be driven by the gear 40 on the shaft 22 for 70 transmitting motion from the centrifugal water spreader to the valve pistons in the vacuum tubes.

A suitable vacuum pressure gage 98 may be connected with the chamber 82 in the 75 tubes 76. The water from the condenser will rise in the separator tanks 77 to a point near the top of the tanks, and necessarily a certain amount of this water will rise in the tubes because of the vacuum therein.

The discharge of the water from the spreader 26 and the flow of the water through the funnels below causes a suction in the chamber 35 which serves to draw the air from the tubes 76 and causes an evacuation 85 thereof, thus producing a partial vacuum in the chamber 35 and the tubes 76.

The arrangement of the cranks on the shaft 86 is such that some one of the ports 81 and also 96 is open all of the time, this arrangement being similar to the crank shaft of an engine, and as the piston rises in the upper chamber 84, the ports are opened and a draft created in the pipes 85 connected with the stack 9, the draft being sufficient to 90 draw the gases from the furnace to a point where the suction caused by the fan 25 may take them up and draw them into the gas chamber 6 of the condenser, and as the cranks 90 operate intermittently and regularly, one at a time, the sets of ports in the tubes 76 are successively opened along the line of tubes in regular order and a perpetual draft in the stack obtained. A small 95 amount of the gases from the furnace will necessarily be drawn into the lower chambers 82 of the tubes 76 when these chambers are in communication with the stack, but the suction in the chamber 35 of the condenser will cause their withdrawal with the air 100 from the chambers, and being mixed with the water in the condenser, they will be condensed with the heavier gases and converted into their constituent elements.

The sediment that results from the condensation of the gases together with the water from the spreader is drawn off through the pipes 69 and stored in the separator tanks 77, the pipes 69 being provided with suitable valves 101 so that any one or 110 more of the tanks may be shut off from communication with the condenser in case of an emergency.

My condenser, as herein disclosed may be 115 made to perform all of the functions of a smoke consumer, and at the same time separate from the gases from the stack all of the valuable metals and particles of matter; it

may be attached to and used in connection with any style of furnace as used for any commercial purpose, and the form may be modified to adapt it to use with the various 5 styles of furnaces.

Having thus described my invention, what I claim as new and desire Letters Patent for, is:

1. A condensing mechanism for a furnace 10 comprising a gas chamber, a centrifugal externally helically vaned water spreading means below said chamber, and means for the discharge of the water therefrom.

2. In a device of the character described, 15 the combination of a condenser adapted to be connected with a furnace and having a gas chamber adapted to receive the gases therefrom; means for separating the heavier elements from said gases and treating them 20 with water; and means for discharging said gases from said chamber for further treatment.

3. In apparatus of the character described, a casing provided near one end with 25 a gas receiving chamber and having a condensing chamber disposed near the gas receiving chamber, a gas supply conduit leading into the gas receiving chamber, a rotatable water spreading element arranged 30 within the condensing chamber, means to supply water into the condensing chamber to impinge against the rotatable water spreading element to drive it, and centrifugally operated means driven by the rotatable water spreading element and serving 35 to automatically regulate the supply of water.

4. In apparatus of the character described, a casing provided with a gas receiving 40 chamber and having a condensing chamber disposed near the gas receiving chamber, a gas supply conduit leading into the gas receiving chamber, a rotatable tubular water spreading element arranged within 45 the condensing chamber and provided upon its exterior with vanes, means to supply water into the condensing chamber to impinge against the rotatable water spreading element to drive it, and a rotatable 50 fan arranged in the gas receiving chamber and near the upper end of the tubular water spreading element, and rotatable therewith.

5. In apparatus of the character described, a casing provided near one end 55 with a gas receiving chamber and having a condensing chamber disposed near the gas receiving chamber, a shell secured to the opposite end of the casing and having an

apertured partition for dividing the same into communicating vacuum and water 60 chambers, outlet means connected with the water chamber, a rotatable tubular water spreading element arranged within the condensing chamber, means for introducing water into the condensing chamber to impinge against the rotatable tubular water 65 spreading element for driving it, a gas supply conduit connected with the gas receiving chamber, and a suction conduit connected with the gas supply conduit and with the 70 vacuum chamber.

6. In apparatus of the character described, a casing provided near one end with a gas receiving chamber and having a condensing chamber disposed near the gas 75 receiving chamber, a shell secured to the opposite end of the casing and having an apertured partition for dividing the same into communicating vacuum and water chambers, a rotatable tubular water spreading element arranged within the condensing chamber, means for introducing water into the condensing chamber to impinge against the rotatable tubular water spreading element for driving it, a gas supply conduit 80 connected with the gas receiving chamber, a suction conduit connected with the gas supply conduit and the vacuum chamber, a valve connected in the suction conduit, and means operated by the rotatable water 85 spreading element for operating the valve.

7. In apparatus of the character described, a casing provided with a gas receiving chamber and having a condensing chamber disposed near the first named chamber, 95 a gas supply conduit leading into the gas receiving chamber, a rotatable tubular water spreading element arranged within the condensing chamber, means to supply water to impinge against the water spreading element to drive it, a fan connected with the water spreading element to rotate therewith and arranged within the gas receiving chamber to draw gas therein from the gas supply conduit, and apparatus actuated by 100 the water spreading element and connected with the conduit at a point remote from its connection with the gas receiving chamber to draw gas in the conduit toward the fan which in turn draws it into the gas receiving chamber.
